SPINDLE MOUNTING

Seddon C. Nelson, Front Royal, Va., assignor to
 American Viscose Corporation, Wilmington,
 Del., a corporation of Delaware

Application August 21, 1945, Serial No. 611,813

10 Claims. (Cl. 57—134)

1

This invention relates to an improved mounting for a spinning and twisting device, and is particularly concerned with the lubrication of ball or roller bearings therein. The present application concerns an improvement in the type of device shown in my application Serial No. 580,409, filed March 1, 1945.

This invention provides improved lubrication of spinning and twisting devices which involve relative rotation between a spindle and a bearing housing between which ball or roller bearings are provided to reduce friction to a minimum. The invention is particularly applicable to spindles which are vertical or inclined to the horizontal so that the ordinary methods of ring lubrication and wick lubrication are ineffective. A particular object of the invention is to provide effective lubrication of ball or roller bearings which are spaced axially along such an inclined or vertical spindle whether the bearing housing rotates about a stationary spindle or whether the spindle is rotated within a bearing housing which is held stationary. The specific objects, features and advantages of the invention will be apparent from the drawing and the description thereof hereinafter.

In the drawing, which is illustrative of the invention—

Figure 1 is a vertical elevation, partially broken away and in section; and

Figure 2 is a transverse section taken on the line II—II of Figure 1.

The invention will hereinafter be described in connection with a form of twister shown in the above mentioned copending application which necessitates the use of a hollow spindle for the passage of one or more yarns being twisted or doubled, but it is to be understood that the hollow character of the spindle is not essential insofar as the lubrication system and mounting arrangement herein described are concerned. That is, the same lubrication system may be applied to a spinning and twisting device of the type which does not require the use of a hollow spindle and may be used in such a device in which the spindle is held stationary, whereas the bearing housing supporting a package-holder as hereinafter described is rotated.

As shown in the drawing, the spinning and twisting device comprises a hollow spindle 2 which carries a pulley or sheath 3 and has an extension 4 carrying a plurality of idling rolls 5, 6 and 7 for the purpose of equalizing the speed of withdrawal of a plurality of yarns from the lower end of the hollow spindle, as more particularly

2

described in my copending application. The spindle is rotatably mounted in the supporting bracket or arm 8 which is formed with an annular bearing housing 9 for receiving the hollow spindle. Ball bearings 10 and 11 and their associated races are provided between the housing 9 and the spindle 2 at spaced points axially of the spindle 2. There is fixedly secured to the lower end of the spindle a container 12 having a cup-like shape for receiving a supply of oil. A portion of the housing 9 which may take the form of a flange 13 extends into the cup-like housing 12 and a passage 14 extends to the outer periphery of the flange 13 and communicates with an annular chamber 15 by means of a connecting passage 16. During the rotation of the container 12, which occurs during operation of the device, the oil therein is thrown against the outer wall thereof, where it is scooped through the flange 13 by means of the passage 14 and forced into the annular chamber 15 in the manner more particularly described hereinafter.

Within the annular chamber 15 there is provided means for feeding oil to the bearings. This means comprises a sleeve 17 secured to the housing 9 at its base and spaced radially from the circumference of the spindle. A sleeve 18 of wicking material such as felt, is stretched around the sleeve 17 and bears against a sloped surface 19 formed on the outer periphery of the spindle just below the upper bearing 11. A collar 20 serves to hold the wick in contact with the tapered surface 19. By this means, oil is directed in a thin film to the tapered surface and centrifugal force and capillary attraction cause the oil to move to the upper bearing, whereas gravitational, adhesion, and surface tension effects cause a portion of the oil to proceed down the spindle to the lower bearing. A cap 21 may be threaded over the bearing housing and has a bore 22 which allows free relative rotation between it and the spindle 2.

There is provided fixed to the spindle above this supporting system a container 32 for oil preferably of cup-like shape as in the mounting below. A bearing housing 33 encloses an annular chamber 34 about the hollow spindle and spaced ball bearings 35 and 36 permit relative rotation between the hollow spindle and the housing 33. The housing 33 has means, in the form of a flange 37 through which a passage 38 is provided for scooping oil thrown centrifugally to the outer wall of the container 32 and directing it into the annular channel 34. A sleeve 38a secured to the housing at its base and spaced radially from the

spindle carries a sleeve 39 of wicking material which is held against the bottom of a tapered portion 40 of the spindle by means of the collar 41 analogous to the structure below.

The housing 33 as shown has fixedly secured thereto a shell 42 which may have a removable cover 43. A weight 44 attached to the shell 42 serves to prevent rotation of the housing 33 during rotation of the spindle. As shown, the housing 33 supports a wound package 45 carried by a cone 46 which fits over the sleeve 33. A hollow thread-guiding tube 47 extends through the nose of the cone 46, and is secured to the sleeve 33, so that it is in alignment with the hollow bore of the spindle but out of contact therewith. Spring tension means may be provided as described in my copending application for tensioning the yarn as it proceeds from the outer windings of the package 45 through the tube 47 to the hollow spindle. One or more radial bores 50 are provided between the supporting bracket mounting and the package-supporting mounting to allow the entry of a yarn coming from a source of supply above the package, as shown and more particularly described in my copending application. This yarn may be rotated about the stationary package 45 and the shell 42 thereabout by means of the more or less hemispherical flyer 51 having suitable projections 52 to engage the yarn.

During rotation of the spindle, the oil in the cup-like containers 12 and 32, is thrown against the internal peripheral walls thereof and rotation of the oil with the container causes a portion of it to be scooped into the passages 14 and 38 respectively. This directs the oil into the annular chambers 15 and 34 in which the wicking means carries it to the juncture of the tapered and cylindrical portions of the external periphery of the hollow spindle. At this juncture, the oil film divides, a portion thereof flowing downward along the cylindrical spindle by gravity until it reaches the lower bearings 10 and 35 respectively. Other portions are caused to flow along the tapered surfaces 19 and 40 by centrifugal force until they flow into the bearings 11 and 36 respectively. Upon stoppage of the spindle, lubricant is retained by the wicking sleeves in readiness to feed lubricant immediately upon starting the bearing again. Any excess lubricant remaining in the annular chambers 15 and 34 largely flows back into the containers 12 and 13 respectively.

The present invention thus provides a simple and efficient lubricating system for assuring an adequate but not excessive supply of lubricant, such as oil, to ball or roller bearings which are spaced widely apart along a spindle inclined sharply to the horizontal. It is to be understood that the description hereof is entirely illustrative and that changes and variations may be made without departing from the spirit of the invention as described in the appended claims.

I claim:

1. A mounting for a spinning and twisting device comprising a spindle, a container for oil fixed to the spindle, a bearing housing about the spindle for supporting a wound package, axially spaced rolling contact bearings between the spindle and housing for permitting relative rotation therebetween, an annular chamber within the housing between the bearings, a passage through the housing communicating with the container and the annular chamber, means within the annular chamber for feeding oil therein to the

bearings, and means for imparting relative rotation to the spindle and housing.

2. A mounting for a spinning and twisting device comprising a spindle, a container for oil fixed to the spindle, a bearing housing about the spindle for supporting a wound package, axially spaced rolling contact bearings between the spindle and housing for permitting relative rotation therebetween, an annular chamber within the housing between the bearings, a passage through the housing communicating with the container and the annular chamber, the container and housing being constructed and arranged for forcing oil through the passage into the annular chamber, means within the annular chamber for feeding oil therein to the bearings, and means for imparting relative rotation to the spindle and housing.

3. A mounting for a spinning and twisting device comprising a spindle, a container for oil fixed to the spindle, a bearing housing about the spindle for supporting a wound package, axially spaced rolling contact bearings between the spindle and housing for permitting relative rotation therebetween, an annular chamber within the housing between the bearings, a passage through the housing communicating with the container and the annular chamber, the container and housing being constructed and arranged for forcing oil through the passage into the annular chamber, means within the annular chamber for feeding oil therein to the bearings comprising a wicking sleeve having an upper portion in contact with the spindle and a portion of the spindle periphery tapering outwardly from the point of contact with the wicking sleeve to a point adjacent the upper roller bearing.

4. A mounting for a spinning and twisting device comprising a spindle, a cup-like container for oil fixed to the spindle, a bearing housing about the spindle for supporting a wound package, axially spaced rolling contact bearings between the spindle and housing for permitting relative rotation therebetween, an annular chamber within the housing between the bearings, a flange on the housing extending into the container, a passage through the flange communicating with the annular chamber and the container adjacent its internal peripheral wall, means within the annular chamber for feeding oil therein to the bearings, and means for imparting relative rotation to the spindle and housing.

5. A mounting for a spinning and twisting device comprising a spindle, a cup-like container for oil fixed to the spindle, a bearing housing about the spindle for supporting a wound package, axially spaced rolling contact bearings between the spindle and housing for permitting relative rotation therebetween, an annular chamber within the housing between the bearings, a flange on the housing extending into the container, a passage through the flange communicating with the annular chamber and with the container adjacent its internal peripheral wall, means within the annular chamber for feeding oil therein to the bearings comprising a wicking sleeve having its upper portion in contact with the spindle and a portion of the spindle periphery tapering outwardly from the point of contact with the wicking sleeve to the upper bearing, and means for imparting relative rotation to the spindle and housing.

6. A mounting for a spinning and twisting device comprising a rotatable spindle, a container

5

for oil fixed to the spindle, a bearing housing about the spindle for supporting a wound package, means tending to maintain the bearing housing stationary, axially spaced ball bearings between the spindle and housing for permitting relative rotation therebetween, an annular chamber within the housing between the bearings, a passage through the housing communicating with the container and the annular chamber, means within the annular chamber for feeding oil therein to the bearings, and means for rotating the spindle.

7. A mounting for a spinning and twisting device comprising a rotatable spindle, a container for oil fixed to the spindle, a bearing housing about the spindle for supporting a wound package, means tending to maintain the bearing housing stationary, axially spaced ball bearings between the spindle and housing for permitting relative rotation therebetween, an annular chamber within the housing between the bearings, a passage through the housing communicating with the container and the annular chamber, the container and housing being constructed and arranged for pumping oil through the passage into the annular chamber, means within the annular chamber for feeding oil therein to the bearings, and means for rotating the spindle.

8. A mounting for a spinning and twisting device comprising a rotatable spindle, a cup-like container for oil fixed to the spindle, a bearing housing about the spindle for supporting a wound package, axially spaced ball bearings between the spindle and housing for permitting relative rotation therebetween, an annular chamber within the housing between the bearings, a flange on the housing extending into the container, a passage through the housing communicating with the annular chamber and with the container adjacent its internal peripheral wall, means within the annular chamber for feeding oil therein to the bearings, and means for rotating the spindle.

9. A mounting for a spinning and twisting de-

6

vice comprising a rotatable spindle, a cup-like container for oil fixed to the spindle, a bearing housing about the spindle for supporting a wound package, axially spaced ball bearings between the spindle and housing for permitting relative rotation therebetween, an annular chamber within the housing between the bearings, a flange housing extending into the container, a passage through the housing communicating with the annular chamber and with the container adjacent its internal peripheral wall, means within the annular chamber for feeding oil therein into the bearings, a wicking sleeve having its upper portion in contact with the spindle and a portion of the external periphery of the spindle being tapered from the point of contact with the wicking sleeve to a point adjacent the upper bearing, and means for rotating the spindle.

10. A mounting for a spinning and twisting device comprising a rotatable spindle, a container for oil fixed to the spindle, a bearing housing about the spindle for supporting a wound package, axially spaced ball bearings between the spindle and housing for permitting relative rotation therebetween, an annular chamber within the housing between the bearings, a passage through the housing communicating with the container and the annular chamber, means within the annular chamber for feeding oil therein to the bearings; another container for oil fixed to the spindle below the first, another bearing housing about the spindle and extending within the second container, a bracket for supporting the second bearing housing, axially spaced ball bearings between the spindle and the second housing for permitting relative rotation therebetween, an annular chamber within the second housing between the bearings, a passage through the second housing communicating with the container and the annular chamber, means within the second annular chamber for feeding oil therein to the bearings; and means for rotating the spindle.
